CLAIM

The ornamental design for a digital audio disc player with amplifier and tuner, as shown and described.

DESCRIPTION

FIG. 1 is a perspective view of a digital audio disc player with amplifier and tuner showing my new design;

FIG. 2 is a front view thereof;

FIG. 3 is a rear view thereof;

FIG. 4 is a top plan view thereof;

FIG. 5 is a bottom view thereof;

FIG. 6 is a right side view thereof;

FIG. 7 is a left side view thereof; and,

FIG. 8 is a front perspective view thereof in a usage state.

The broken line showing on the drawing disclosure is for illustrative purposes only and forms no part of the claimed design.
